Application December 15, 1951, Serial No. 261,872

8 Claims. (Cl. 99—295)

This invention relates to a method of and means for preparing individual servings of beverage by passing fluid through a cartridge containing fluid-soluble ingredients.

An object of the invention is to provide a device for enabling a layman, or other person unskilled in the culinary arts, to prepare an individual serving of beverage by simply associating a cartridge containing fluid-soluble ingredients with a fluid dispensing device which may be manually actuated for discharging a quantity of fluid directly into the cartridge for thereby enabling the fluid to dissolve the fluid-soluble ingredients of the material contained within the cartridge.

Another object of the invention is to provide such a device wherein a single lever is provided for controlling the various sequential operations performed on the cartridge, whereby the user of the device need not be concerned with manipulation of a plurality of items.

A further object of the invention is to provide a fluid dispensing nozzle having associated therewith a cartridge carrier reciprocably mounted for axial movement toward and away from the nozzle, wherein actuation of a single lever is utilized for sequentially moving the cartridge carrier for advancing the cartridge into connected relationship with the nozzle, and then operating a suitable valve for discharging a quantity of fluid through the nozzle directly into the cartridge; said cartridge being retractable from the nozzle only after the valve which controls the flow of fluid through the nozzle has been closed.

Still another object of the invention is to provide a device having cartridge holding and advancing means which may be shifted to a cartridge releasing position incident to movement of the hereinabove mentioned manually operable lever or handle to a predetermined position, thereby enabling the user of the device to quickly and expeditiously discard a used cartridge without having to touch same.

Another object of the invention is to provide a beverage dispensing device which includes a container for fluid and means for heating fluid therein to temperatures high enough to dissolve the desirable fluid-soluble ingredients of material housed within a cartridge through which the heated fluid is discharged. Heretofore considerable difficulty has been experienced in those instances when the vapor pressure is reduced in a closed fluid container of the type wherein vapor pressure is utilized to eject the heated fluid therefrom incident to removal of say 40% of the original volume of fluid, whereby the rate of fluid discharge is materially lessened, thereby impairing the desired operational characteristics of the prior art devices.

I have simply yet effectively alleviated this condition by providing means responsive to the pressure conditions existing within the fluid container for automatically generating additional vapor pressure when the vapor pressure in the container falls below a certain predetermined value.

I have likewise provided alternate means for insuring the proper discharge of fluid, which means are entirely

2

independent of the pressure conditions within the container.

5 A further object of the invention is to provide a vapor booster pump the operating characteristics of which are such as to materially increase the vapor pressure within the container without appreciably increasing the temperature of the fluid in said container.

Another object of the invention is to provide a cartridge for housing material containing fluid-soluble ingredients 10 which is so constructed and arranged as to insure maximum turbulence of its contents incident to the passage of fluid therethrough.

Still a further object of the invention is to provide a device having the hereinabove described characteristics 15 and which includes simple yet highly effective means for enabling it to be supported by, or suspended from, practically any type of conveniently available support means, thereby greatly enhancing its utility.

Another object of the invention is to provide a waste receptacle in association with the device, wherein said waste receptacle is so disposed as to receive the spent cartridges, and provide a drip or catch pan for fluid accidentally or otherwise spilled incident to use of the device.

25 Still another object of the invention is to provide a device wherein the cartridge holding and advancing means is operatively and structurally associated with the nozzle and its valve whereby to provide a compact, highly efficient unit.

30 These and other objects are attained by the means described herein and as disclosed in the accompanying drawings, in which:

Fig. 41 is a sectional view taken on line 41—41 of Fig. 40.

Fig. 42 is a sectional view of a device, embodying the teachings of the present invention, provided with means independent of the pressure conditions within the container for effecting a positive discharge of fluid therefrom.

With particular reference now to Figs. 2 and 4, the numeral 50 denotes generally a container for fluid such as, by way of example, water which is to be heated for use in the preparation of a hot beverage. This container may include integrally formed side and bottom walls and a top closure plate 52 provided with an opening 54 for the reception of a filler tube 56 depending from ferrule 58 having an annular seat 59 suitably engageable by plate 60 of a suitable closure element indicated generally by the numeral 62.

In the preferred embodiment of the invention a tube or pipe 64 interconnects the interior of the ferrule 58, above closure plate 60, with the interior of an open-bottom chamber denoted generally by the numeral 66, located beneath container 50, thereby normally venting the space immediately above closure plate 60 to the atmosphere.

A conduit 68 (Fig. 2) terminates in a lower end 70 disposed interiorly of and adjacent the lower portion of the container, the opposite end of said conduit communicating with passageway 72 which is in open communication with a nozzle denoted by the numeral 80 in Fig. 5.

Suitable means such as, by way of example, a pair of independently operable heating coils 76 and 78 are provided for heating fluid housed within container 50 and for generating a vapor pressure within the container above the fluid sufficient to effect a discharge of heated fluid via conduit 68.

With particular reference now to Figs. 5 and 6, the numeral 80 denotes a nozzle and the numerals 82 and 84 denote a pair of side plates mounted for reciprocable motion relative to nozzle 80, the lower end of said side plates terminating in inturned members 86 and 88, respectively, for providing a cartridge carrier.

The upper portions of plates 82 and 84 may engage the outer face of a pair of laterally spaced downwardly depending duplicate cam plates 90 rotatable with and about the axis of shaft 92 which, in Figs. 5 through 13, comprises the axis of rotation of the plug of a standard two-way valve. Compression springs 94 interposed between washers 96 and cotter pins 98 secured to opposite ends of shaft 92 may be utilized for yieldingly maintaining plates 82 and 84 in desired relationship with cam plates 90.

10 As best illustrated in Figs. 6, 7, 11, 12 and 14, duplicate cam tracks 100 are provided in each of plates 90, said cam tracks including interconnected portions 102 hereinafter referred to as the cartridge carrier actuator portion and an arcuate portion 104 having its center on shaft 92, portion 104 being hereinafter referred to as the valve actuating portion.

A pin 106 spanningly engages the upper ends of the cartridge carrier plates 82 and 84, extending through suitable axially aligned apertures therein, said pin being received within vertical slot 108 provided in the valve housing for thereby limiting movement of the pin in a substantially vertical plane in axial alignment with the center of shaft 92, see Fig. 7.

20 The lower portions of the cartridge carrier plates 82 and 84 are normally and yieldably urged toward one another by means of a spring 110, the opposite ends of which are suitably anchored to said plates, see Figs. 6 and 7.

25 An element 112 is secured to and carried by the lower portion of the valve housing adjacent the nozzle, wherein the overall width of said element is of a dimension approximating the lateral spacing of the cartridge carrier plates 82 and 84 when they are in the position illustrated in Figs. 5 through 10. A pair of downwardly and outwardly inclined camming ears 114 may be formed integral with element 112, said ears projecting outwardly through a substantially rectangular slot 116 provided in each of plates 82 and 84.

30 As best illustrated in Figs. 5, 7, 8 and 9, a stop member 120 is formed integrally with or secured to and carried by the rearward portion of each of inturned elements 86 and 88. A pair of inturned spring guide members 122 are provided for defining a throat 124 into which the upper portion of a cartridge is receivable, members 122 functioning as resilient guide elements. One end of each guide member may be fixedly secured to a side plate such as by rivets 121, or the like, the other free end 123 abutting a stop member 120, as illustrated.

35 With reference now to Figs. 15-18, the numeral 130 denotes generally a cartridge which includes a body portion 132 terminating in an upper portion 134 and a lower open bottom portion 136. The dimensional characteristics of upper portion 134 are such as to provide a neck 138 immediately below an enlarged bearing portion 140, it being noted that the neck portion 138 is receivable within throat 124 for thereby positioning the overhanging portion 142 of portion 140 in overlapping relationship with portions of bottom plates 86 and 88 of the cartridge carrier plates 82 and 84.

40 As best illustrated in Fig. 18, a quantity of fluid soluble material, indicated generally by the numeral 144, is housed within cartridge 130, being maintained therein by reason of a water pervious member 150. Preferably a membrane 152 spans top opening 154 of the cartridge, thereby effectively sealing the contents of the cartridge against the effects of atmospheric conditions.

45 The structural characteristics of all of the cartridges are preferably such as to agitate the material housed therein incident to a flow of fluid therethrough. In the cartridge illustrated in Figs. 15 through 18 the maximum diameter is from 100 to 175 percent of the height dimension, said maximum diameter being from 8 to 14 times the diameter of the upper portion at the neck.

50 In use the neck of a cartridge may be introduced into

throat 124 for association with lips 86 and 88 of the cartridge carrier plates 82 and 84 during those periods of time when handle 149 is in the neutral position illustrated in Figs. 5, 6 and 7. It will be noted that when the handle is in the neutral position the pin or cam follower 106 is disposed in cam slot 102 adjacent but spaced an appreciable distance from lower end 153 thereof. If lever 149 is now shifted in a clockwise direction, with reference to Figs. 6 and 7, cam follower pin 106 will be moved upwardly in slot 102 for thereby lifting plates 82 and 84 upwardly and the upper portion of the cartridge will be advanced to engagement with the lower end of nozzle 80.

The forward end of nozzle 80 may terminate in an outwardly projecting hollow stud 160 dimensioned to enter portion 154 of the cartridge whereby further movement of the cartridge toward the nozzle will result in membrane 152 being ruptured, sheared or displaced by stud 160 thereby establishing open communication between nozzle 80 and the interior of cartridge 130. Preferably resilient sealing means denoted generally by the numeral 170 may be provided on nozzle 80 for effecting a fluid tight fit between the upper portion 140 of a cartridge and nozzle 80.

If handle 149 now be moved further in a clockwise direction, cam follower or pin 102 will ride within arcuate cam slot 104 for maintaining the cartridge carrier plates 82 and 84 in the fully elevated position illustrated in Figs. 10 through 12 while the valve is progressively opened for permitting discharge of hot fluid via conduit 68 and pipe 72 to nozzle 80, it being noted that such fluid will be discharged directly into the interior of the cartridge.

The flow of hot fluid into and through the cartridge will permit the fluid-soluble ingredients of material 144 to dissolve and enter into solution and thence be discharged through member 150 thence into a cup or the like securely though releasably carried by a clamping member 180.

After the desired quantity of fluid has been passed through the cartridge, actuation of lever 149 toward the neutral position of Figs. 5, 6 and 7 will result in the closing of the valve and then a lowering of the cartridge carrier plates 82 and 84 for retracting the cartridge from the nozzle and returning same to the position illustrated in Figs. 5 and 7. After the flow of fluid has thus been terminated, the cup or other container into which the beverage has been dispensed may be removed, after which lever 149 may be shifted in a clockwise direction on the other side of its neutral position for thereby forcing the cartridge carrier plates 82 and 84 downwardly whereby the upper edge 172 of rectangular slots 116 will ride outwardly on cam ears 114 for shifting or spreading the lower portions of plates 82 and 84 apart for disengaging the upper portion of cartridge 130, see Fig. 13. Springs 122 are compressed, that is, spread apart when a cartridge is seated in notches 125 of inturned members 86 and 88. When the lower ends of plates 82 and 84 are shifted apart as in Fig. 13, springs 122 eject the upper portion of the cartridge from notches 125.

In the preferred embodiment of the invention, container 50 is housed within an outer unit or jacket 200 including top walls 202, side walls 204, rear wall 206 and a front wall 210, it being noted that suitable insulation means are provided between adjacent portions of container 50 and the housing. The lower ends of the housing may be reinforced by a panel including a top 177, sides 179 and a pair of laterally spaced inturned track members 181 which are dimensioned to engage the overhanging side edge or lip portions 182 of a waste receptacle 184 suspended therefrom, see Fig. 1. The waste receptacle includes an aperture in axial alignment with nozzle 80 for accommodating used cartridges and quantities of waste fluid.

Considerable difficulty was formerly encountered after a portion of the fluid initially housed within container 50 had been discharged through conduit 68 by reason of the reduction in the vapor pressure utilized to expel the hot fluid from the container. I have simply and effectively obviated this difficulty by means of the vapor pressure booster pump illustrated in Fig. 4. The pressure within chamber 50 is transmitted to diaphragm 190 of an auxiliary chamber 192 in open communication with chamber 50 as at 194. A micro switch 196 having a contact finger 198 is suitably mounted so that finger 198 will be elevated for thereby breaking the electrical circuit which would otherwise be established in conduits 230 and 232, which are series connected with a suitable heating element denoted generally by the numeral 234. This heating element is constructed and arranged whereby to provide a localized spot of high intensity heat within a domed chamber 236. A riser tube 238 extends between and is in open communication with the upper portion of chamber 236 and the upper interior of container 50. An aperture 240 is provided in the wall of chamber 236 for facilitating the introduction of small quantities of fluid from container 50 into chamber 236.

During those periods of time when the vapor pressure existing within container 50 is equal to or in excess of a desired and predetermined amount, diaphragm 190 will be flexed outwardly thereby elevating finger 198 of the micro switch for breaking or interrupting the electrical circuit to heating element 234. However, whenever the vapor pressure within container 50 shall fall below a predetermined minimum, such as, by way of example, will occur when 40% or more of the fluid initially in the container has been withdrawn, diaphragm 190 will assume the condition illustrated in Fig. 4, thereby lowering finger 198 of the switch for thereby closing the electrical circuit to heater coil 234. Initial energization of coil 234 will result in heating of the fluid housed within chamber 236 whereby such fluid will be ejected upwardly through tube 238, thereby emptying the chamber. Additional fluid will then enter the chamber via opening 240 which fluid will be rapidly vaporized and discharged as a highly heated vapor upwardly through tube 238 for thereby increasing the vapor pressure existing within container 50. The operation of the vapor pressure booster pump does not appreciably increase the temperature of the residue of fluid in the container although it does materially increase the pressure head under which the fluid is ejected via conduit 68.

In this manner I have provided simple, effective, fully automatic means for compensating for the decrease in vapor pressure which would otherwise occur incident to operation of the device.

With reference now to Figs. 27-39, I have illustrated a preferred embodiment of a combined valve and cartridge carrier actuator. The numeral 300 denotes a housing having front, rear and side walls 302, 304 and 306 terminating in a tubular nozzle 308. An O-ring 310 is seated within an annular seat in the outer face of the nozzle. A chamber 312 has an inlet 314 and lower and upper bores or outlets 316 and 318 of the same cross sectional area. A slot 301 including side and bottom walls 320 and 322 is provided in the housing with side walls 320 in substantial parallelism with outer side walls 306.

65 A cam plate 326 is pivotally secured as at 328 to and between side walls 320 of slot 301.

A valve stem or plunger 330 is mounted for axial reciprocable movement within bores 316 and 318, said valve stem being provided with a pair of laterally spaced O-rings 332 and 334 seated within suitable annular seats provided in the outer face of the plunger.

As best illustrated in Fig. 32, O-ring 332 is adapted to make sealing engagement with bore 316 when the valve stem has been shifted to its lowermost, or closed position. O-ring 334 sealingly engages bore 318 thereby

precluding the accidental or unintentional discharge of fluid upwardly through this bore. When the valve stem is located as illustrated in Fig. 32, fluid under pressure within chamber 312 via inlet 314 will be contained within chamber 312.

In the preferred embodiment of the invention the upper end of the valve stem or plunger 330 terminates in or is provided with a head or cam follower portion 336 engageable by the lower camming surface 338 of cam plate 326. A spring 340 interposed between bottom wall 322 of slot 301 and the underside of head 336 normally exerts a valve stem lifting force which will maintain head 336 in contacting relationship with camming face 338 at all times.

With reference now to Fig. 33, it will be noted that movement of cam 326 in a counter-clockwise direction will result in upward movement of the valve stem, thereby shifting O-ring 332 upwardly and out of engagement with bore 316 for permitting discharge of fluid from chamber 312 via bore 316. It will be noted that O-ring 334 engages the inner wall of bore 318 thereby precluding discharge of fluid upwardly through this bore. The tapered construction at 342 enables an operator to accurately control the rate of fluid discharge via bore 316, it being noted that lowering of the valve stem will progressively restrict and then terminate the rate of discharge, whereas further elevation of the stem will further increase the rate of discharge via stem 316.

The cartridge carrier comprises a pair of side plates 360 having lugs 361 provided on their side edges. The lower portions of plates 360 are inclined outwardly and downwardly as at 362, thence downwardly as at 364 and then turned inwardly as at 366, to provide a combined cartridge engaging and camming unit. Plates 360 are mounted for reciprocable motion along the outer side walls 306 of housing 300, and in the preferred embodiment of the invention these plates are interconnected by a pin 368 which extends through a vertical slot 370 provided through side walls 320 of slot 301, and through a cam slot 372 in cam plate 326.

With reference now to Fig. 33, it will be noted that movement of cam 326 about pivot 328 will result in relative motion between plates 360 and the valve housing during those periods of time when pin 368 is in that portion 367 of the cam slot which is not disposed on a radius with respect to pivotal connection 328. It will likewise be noted that when pin 368 is seated within those portions 369 of the cam slot which are radially disposed with respect to pivot connection 328 (as illustrated in Fig. 33), the said side plates will not be moved relative to housing 300 incident to movement of cam 326 throughout an arc restricted to the arcuate portion 369 of cam slot generally denoted by the numeral 372.

Those portions of plates 360 remote from pin 368 are normally urged together and in contacting relationship with the side faces of housing 300 by means of a spring 374 which, as best illustrated in Figs. 33 and 38, spannably engages these plates.

A second pair of plates 380 are carried by and fixedly secured to the front and rear walls 302 and 304 of the housing such as by means of set screws 382 (Figs. 33 and 35), wherein each of these plates is provided with flanges 381 having slots 383 for slidably receiving lugs 361 of plates 360. The lower end of each of plates 380 is provided at its lower end with a pair of camming ears 384, which, as best illustrated in Fig. 35, are adapted to engage the outwardly and downwardly inclined portions 362 of the axially reciprocable cartridge carrier plates 360 for forcing or spreading the lower ends apart, thereby shifting inturned portions 366 laterally apart to a cartridge releasing position.

With particular reference now to Fig. 28, it will be noted that hand grip portion or lever 400 is in a so-called neutral position for disposing the various structural elements in the relative positions indicated in Fig.

27. Referring back now to Fig. 28, it will be noted that pin 368 is disposed adjacent but spaced from the lower end 402 of the non-arcuate portion 367 of cam slot 372. If the lever is now shifted to the left, that is, in a counter-clockwise direction about pivotal connection 328, pin 368 will ride upwardly in the non-arcuate portion of cam slot 372 for lifting side plates 360 upwardly from the position illustrated in Fig. 28 to the positions illustrated in Figs. 30 and 31. As best illustrated in Fig. 30, it will be noted that no axial movement is imparted to valve stem or plunger 330 incident to travel of pin 368 through the non-arcuate portion 367 of the cam slot. During this sequence the upper portion 410 of a cartridge 412 is lifted upwardly from the lowered position illustrated in Fig. 27 to the fully advanced or elevated position illustrated in Fig. 32 in which the neck portion of the cartridge is in fluid-tight engagement with O-ring 310, thereby effecting a fluid-tight seal with the lower annular portion 308 of the nozzle.

20 Further movement of lever 400 in a counterclockwise direction will result in elevation of valve stem 330 as illustrated in Fig. 33 for enabling the operator to accurately control the rate of fluid discharge via bore 316.

25 After the desired quantity of fluid has thus been discharged into and through a cartridge, the lever may be retracted, that is, moved in a clockwise direction for shifting valve stem downwardly to the fully closed position illustrated in Fig. 30. Further clockwise movement of the lever will result in lowering of the cartridge carrier 30 plates 360 to the position indicated in Fig. 27.

30 If lever 400 is now shifted on the other side of the neutral position of Fig. 28, that is, in a clockwise direction with reference to pivotal connection 328, side plates 360 will be forced downwardly whereby portions 362 will engage and then ride outwardly on camming ears 384, see Fig. 35.

35 In Figs. 32, 40 and 41, I have illustrated another modification of cartridge which has been constructed in such a manner as to insure thorough wetting and agitation of the material housed within the cartridge. With particular reference to Figs. 40 and 41, the numeral 420 denotes a cap including an inner annular wall 422 dimensioned to make snug fit with O-ring 310 for effecting a fluid-tight fit between nozzle 308 and the cartridge. 45 Preferably a plurality of tabs 424 are struck from the cap bottom 426 for imparting a definite nozzle-action to fluid discharge via nozzle 308 into the interior of cartridge 412.

40 In the preferred embodiment of the invention means are provided for heating the fluid by means of resistor type heating elements indicated generally in Fig. 4 by the numerals 76 and 78, wherein these heating elements may be optionally operated on 110 volt A. C. or 27½ volt D. C. to impart maximum flexibility-of-operation to the device.

50 55 By thus providing two separate heating elements, I am able, when operating on 27½ volts, to utilize both of them for rapidly bringing the fluid up to desired temperature after which one may be cut out, thereby utilizing the other to maintain the fluid at desired temperature.

60 65 With particular reference now to Fig. 22, resistor elements 500 and 502 comprise heating element 76 of Fig. 4 and resistor elements 504 and 506 constitute element 78 of Fig. 4. Resistor element 234 is composed of resistor elements 508 and 510.

70 75 I shall first describe the electrical circuit when the device is operated on 110 volt A. C. in which event terminals 512 and 514 are utilized. The electrical circuit comprises conductor 516 connected to one side of a three-pole switch 518 having contact arms 520, 522 and 524 suitably interconnected for synchronous operation to "on" and "off" positions. Points or contacts 530, 532 and 534 are selectively engageable by their respective contact arms 520, 522 and 524 for completing an electrical circuit with conductor 526. A pilot light 528 is connected in series with contact 534 and conductor 526.

through conductors 536 and 538 whereby said pilot lamp will be energized whenever switch 518 has been closed, said switch and pilot light being illustrated in Figs. 1 and 2 and denoted by the numerals 518 and 528, respectively. A resistor 540 interconnects conductor 516 with conductor 542 which is connected with contact arm 524, thereby reducing the voltage delivered to pilot lamp 528 from 110 to 27½ volts.

Closure of switch 518 energizes contact arms 544 and 546 of a pair of thermostats denoted generally by the numerals 548 and 550, respectively. Thermostat 548 is operatively associated with heater element 76 through contacts 552, conductor 554, 547, thence through heating element 78 and conductor 526, thereby completing a series electrical circuit through heating elements 76 and 78.

In the preferred embodiment of the invention thermostat 548 may be set for temperature approximating 190° F. and thermostat 550 at 185° F. During those periods of time when the temperature of the fluid is less than 185° F. both thermostats will be closed, and an electrical circuit through a second pilot light 560 will be completed via contact point 562, conductor 564, 566, resistor 568 and conductor 570. Elevation of the fluid temperature above 185° F. will result in breaking the circuit to the pilot lamp at arm 546 and contact point 562.

In this manner I have provided simple yet highly effective means for visually indicating those periods of time when the electrical circuit is closed for operating the device and for further indicating when the fluid is above or below the temperature setting of thermostat 550.

When the device is operated on 27½ volts contacts 572, 574, 576 and 578 are suitably connected to one side of the circuit and contacts 580, 582 and 584 to the other side of the circuit. When switch 518 is closed pilot lamp 528 is placed in series with contacts 572 and 580 via conductor 542, arm 524, contact point 534 and conductors 536, 538 and 526 for indicating the electrical circuit has been closed.

When thermostat 548 is closed, relay 586 will be energized via contact 574, conductor 588, 590, 516, arm 520, contact 530, arm 544, contact 552, conductors 554, 592 and contact 584, thereby closing a circuit across points 594 and 596 to place resistor coil 500 in series with contacts 574 and 584 via conductors 598 and 592, and at the same time place resistor 502 in series with contacts 574 and 582 via conductors 598, 547 and 549. In this manner both resistors which collectively comprise heating unit 76 are simultaneously energized.

When thermostat 550 is closed, relay 600 is energized via contact 578, conductors 602, 604, 564, contact 562, arm 546, contact 532, arm 552, conductor 606, 516, arm 520, contact 530, arm 544, contact 552, conductor 592 and contact 584 for closing a circuit across points 608 and 610 to place resistor coil 504 in series with contacts 578 and 580 via conductors 612 and 526, while simultaneously placing resistor coil 506 in series with contacts 578 and 582, via conductors 612, 547, and 549.

From the foregoing it will be observed that resistor coils 504 and 506 can be energized only when both thermostats are calling for heat, however coils 504 and 506 will be de-energized whenever either of the thermostats are opened thereby affording an appreciable saving in electrical energy.

In the lower part of Fig. 22 the electrical circuit to resistor element 234 is disclosed, it being noted that the resistor comprises coils 508 and 510 in series for enabling operation on 27½ D. C. or 110 v. A. C.

When operated on 27½ volts, coil 508 is placed in series with contacts 620 and 622 via conductors 626, 230, switch 196 and conductor 628.

On 110 volts coils 508 and 510 are series connected across contacts 622 and 624 via conductors 232, 230, switch 196 and conductor 628.

In Figs. 19-21 I have illustrated a modified form of cartridge denoted generally by the numeral 1300 which comprises a body portion 1320 including an upper portion 134 similar to the upper portion of the cartridge illustrated in Figs. 15-18. A fluid pervious member 1500 is suitably associated with the lower peripheral edge of body 1320 for retaining fluid soluble material, thereby completing the cartridge assembly.

In Figs. 24 and 25 I have illustrated a cartridge having an upper portion 700 dimensioned to engage an O-ring 310 of nozzle 308. Tabs 762 are provided in wall 704 for imparting a definite nozzle-action to fluid discharged into the interior of the cartridge.

If desired the body 705 of the cartridge may be dome-shaped and fabricated from any suitable material. A sheet of fluid pervious material 706 may be secured to and across the open bottom edge of the housing by any suitable means, such as, by way of example, an inturned lip 708 of a peripheral flange 710. This flange may be engaged by or received between a pair of spaced members 720 and 722 secured to and carried by each of a pair of reciprocably mounted cartridge carrier plates 712 and 714.

In Fig. 25 the numeral 730 denotes a fluid pervious housing which is substantially bag-shaped with its upper end secured to a cap member 732 as at 734. A fluid conduit 736 is secured to and projects through the cap, terminating well within the housing in a deflector element 738. The opposite end of the conduit projects outwardly from cap 732 for insertion into an O-ring 740 carried by lips 742 of reciprocable plates 744. Upward movement of plates 744 will compress the O-ring against the free lower end of nozzle 746 and onto conduit 736 thereby providing a fluid tight connection between the cartridge and nozzle.

A shield 748 may be provided for guiding the upper end of conduit 736 into axial alignment with the nozzle and O-ring assembly, and by mounting the shield to plates 750 reciprocable with plates 744 automatic ejection of a cartridge may be expeditiously effected.

In Fig. 26 I have illustrated a manually operable latch-type of cartridge clamp which includes a cartridge carrying element 760 pivotally secured at 762 to a flange 764 surrounding the fluid discharge nozzle 766 for movement between the operative position indicated in solid outline, and the inoperative position in broken outline.

A cartridge 768 having a hollow body portion 770, a fluid pervious member 722 and a recessed nozzle receptive portion 744 is receivable within element 760 which may be securely though releasably locked relative to the nozzle by means of latch member 776, for disposing the cartridge in fluid tight relationship with the nozzle.

Upon release of latch 776 element 760 will swing downwardly under its own weight to the position illustrated in broken outline for automatically ejecting the cartridge as it strikes against abutment 778 projecting from side wall 780 (see also Fig. 1).

With reference now to Fig. 42, I have illustrated means for insuring discharge of fluid from container 50 to the valve, via conduit 68, which is entirely independent of the pressures within the container. Such alternate fluid delivery means comprises, generally speaking, a suitable fluid pump, such as, by way of example, a so-called centrifugal pump, denoted generally by the numeral 820 having an impeller 822 in driven connection with shaft 816, the upper end of which is suitably connected in driven relationship with an electric motor 810.

In the preferred embodiment of the invention, shaft 816 is housed within a tube 814 suitably sealed as at 812 and 818 for precluding the escape or venting of fluid and/or vapor pressure from the interior of the container 50.

A switch 800 having a spring loaded, reciprocably mounted, actuator pin or arm 802 may be mounted adjacent valve lever 149 for opening the switch during those

periods of time when the lever is in its neutral and/or cartridge release position. Whenever lever 149 is pulled forwardly from its neutral position for advancing or elevating the cartridge carrier and then opening the valve, the switch will be automatically closed for completing an electrical circuit via conductors 806 and 808 to the motor 810.

In this manner I have provided positive means for effecting discharge of fluid within the container regardless of the temperature of the fluid and independent of the vapor pressure within said container.

From the foregoing it will be noted that I have provided simple yet highly effective means for attaining the stated objects.

It should be understood that various changes in the structural details of the device may be made, within the scope of the appended claims, without departing from the spirit of the invention.

What is claimed is:

1. In apparatus of the character disclosed, the combination of a fixed nozzle, a cartridge including an upper end terminating in an upstanding neck portion dimensioned to receive the end of the nozzle, a cartridge carrier reciprocably mounted relative to the nozzle, said carrier including separable jaws for securely though releasably engaging the neck portion of a cartridge for disposing it in axial alignment with said nozzle, a valve for controlling flow of fluid through said nozzle, a lever pivotally mounted relative to said carrier and valve, means operatively interconnecting said lever with means for reciprocating the cartridge carrier and with means for actuating the valve and for correlating the operational characteristics of said last two mentioned means, said lever having a neutral position in which the carrier is disposed in retracted relationship with said nozzle and with the valve closed, said lever shiftable in one direction for initially advancing the carrier toward the nozzle for introducing and then sealing the end of said nozzle into the neck portion of a cartridge suspended from said jaws, and for locking said carrier and cartridge in advance position relative to the nozzle, said lever shiftable further in the same direction away from its neutral position to progressively open the valve for discharging fluid from the nozzle into the neck of the cartridge associated therewith, said lever shiftable back toward its neutral position for sequentially closing the valve and then retracting the carrier for withdrawing the cartridge from the nozzle, and means operable incident to shifting the lever in the other direction from its neutral position for shifting apart the separable cartridge engaging jaws for releasing the cartridge.

2. In apparatus of the character disclosed, the combination of a valve comprising a body portion including a depending nozzle having an axial bore therethrough with the lower end of the bore tapering toward the free end of the nozzle, a valve stem axially shiftable in said bore, sealing means secured to and carried by the valve stem engageable with the bore for controlling the flow of fluid therethrough, spring means normally shifting said stem to retracted valve-opening position, a cartridge carrier including a pair of depending jaws carried by and slideable on said body portion, a first cam for advancing said stem to valve closing position, a second cam for selectively advancing and retracting the jaws relative to the housing, said first and second cams mounted for concurrent movement about a common pivot secured to and carried by said housing, the actuating characteristics of said cams being correlated whereby the valve stem will be positively maintained in a fully lowered, valve-closing position until after the other cam has been actuated for fully advancing the cartridge carrier toward the valve and for locking same in fully advanced position.

3. In an infusion unit for a beverage maker of the type employing a dispensable cartridge containing fluid-soluble ingredients, the combination of a valve comprising

ing a body portion including a depending nozzle, a cartridge carrier including a pair of depending, laterally separable jaws which define a throat arranged to receive the neck of a cartridge, means normally and yieldably urging said jaws to a closed cartridge-supporting position, said cartridge carrier carried by and slideable axially of said body portion, valving means within said body portion operable for controlling the flow of liquid through said nozzle, cartridge carrier shifting means operable for axially advancing and retracting the jaws relative to the housing, a common actuating lever for said valving means and said cartridge carrier shifting means, means interconnecting said lever to each of said last two mentioned means whereby upon movement of said lever the valving means remains inoperable for dispensing liquid through the nozzle until after the lever has been advanced until the cartridge carrier shifting means has been fully advanced toward the valve housing and then locked in said fully advanced position against further axial movement, and whereby reverse movement of said lever actuates the valving means for interrupting the flow of liquid through the nozzle while the cartridge carrier remains in its fully advanced position, said cartridge carrier shifting means being then operable upon further reverse movement of the lever for lowering the carrier away from the valve housing.

4. In an infusion unit for a beverage maker of the type employing a dispensable cartridge containing fluid-soluble ingredients, the combination of a valve comprising a body portion including a depending nozzle, a cartridge carrier including a pair of depending jaws carried by and slideable axially of said body portion, a valving means within said body portion operable for controlling the flow of liquid through said nozzle, cartridge carrier shifting means operable for axially advancing and retracting the jaws to positions above and below an initial position below the nozzle, means normally urging said jaws to a closed cartridge-supporting position, jaw separating means operable to open the jaws to a cartridge-releasing position, a common actuating lever for said valving means, said cartridge carrier shifting means and said jaw separating means, means interconnecting said lever to said last three mentioned means whereby upon movement of the lever the valving means remains inoperable for dispensing liquid through the nozzle until after the cartridge carrier shifting means has been fully advanced toward the valve housing and then locked in said fully advanced position against further axial movement, and whereby reverse movement of said lever actuates the valving means for interrupting the flow of liquid through the nozzle while the cartridge carrier remains locked in fully advanced position, said cartridge carrier shifting means being then operable for lowering the carrier away from the valve housing to its initial position below the nozzle, said cartridge carrier shiftable below its initial position and said jaw separating means rendered operative upon further reverse movement of the lever for automatically releasing a cartridge suspended from said jaws.

5. In an infusion unit for a beverage maker of the type employing a dispensable cartridge containing fluid-soluble ingredients wherein the cartridge includes an upper fluid-inlet portion defined by an upstanding neck circumscribed by a peripheral lip and having a rupturable sealing membrane spanning said neck, the combination of a valve comprising a body portion including a depending nozzle terminating in a shearing surface, a cartridge carrier including a pair of depending, laterally separable jaws which define a throat arranged to receive the neck of a cartridge, means normally and yieldably urging said jaws to a closed cartridge-supporting position, said cartridge carrier carried by and slideable axially of said body portion, valving means within said body portion operable for controlling the flow of liquid through said nozzle, cartridge carrier shifting means operable for axially ad-

vancing and retracting the jaws relative to the housing, a common actuating lever for said valving means and said cartridge carrier shifting means, means interconnecting said lever to each of said last two mentioned means whereby upon movement of said lever the valving means remains inoperable for dispensing liquid through the nozzle until after the lever has been advanced until the cartridge carrier shifting means has been fully advanced toward the valve housing for introducing the nozzle into the neck of the cartridge and forcing the shearing surface of the nozzle through the sealing membrane of the cartridge for establishing open communication between the interiors of the nozzle and cartridge and after the carrier has been locked in said fully advanced position against further axial movement, and whereby reverse movement of said lever actuates the valving means for interrupting the flow of liquid through the nozzle while the cartridge carrier remains in its fully advanced position, said cartridge carrier shifting means being then operable upon further reverse movement of the lever for lowering the carrier away from the valve housing and removing the cartridge from the nozzle.

6. In apparatus of the character described, the combination of a fixed nozzle, a disposable cartridge containing fluid-soluble ingredients, said cartridge including an upper fluid inlet portion comprising an upstanding neck circumscribed by an overhanging peripheral lip, said neck receivable over the end of the nozzle, a valve for controlling passage of fluid through the nozzle, a cartridge carrier reciprocably suspended from said valve, said carrier including a pair of depending, laterally separable jaws having inturned lower ends receivable under the overhanging lip of a cartridge for suspending the cartridge therefrom, a lever, a cam, means interconnecting the lever to said jaws through said cam and actuated by said lever for advancing the carrier axially toward the nozzle for inserting the end of the nozzle into and in fluid-tight engagement with the neck of the cartridge, said cam including means for locking said carrier in advanced, elevated position relative to the nozzle during further movement of the

lever in the same direction for opening and closing the valve.

7. A device as described in and by claim 6, wherein the neck of the cartridge includes means for distributing fluid discharged from the nozzle into the cartridge, whereby the entire contents of the cartridge are thoroughly wetted and agitated incident to the flow of fluid therethrough.

8. A device as described in and by claim 6, wherein the neck of the cartridge is of a diameter less than one-half the maximum diameter of the body of the cartridge.
